UNITED STATES PATENT OFFICE.

DANIEL P. FAHRNEY, HARRY EUGENE DORAN, AND GEORGE ATWELL
NEWTON, OF SPRINGFIELD, MISSOURI.

HOSE-CO尤LING FOR CARS.

No. 825,117.

Specification of Letters Patent.

Patented July 3, 1906.

Application filed October 19, 1905. Serial No. 283,414.

To all whom it may concern:

Be it known that we, DANIEL P. FAHRNEY, HARRY EUGENE DORAN, and GEORGE ATWELL NEWTON, citizens of the United States, and residents of Springfield, in the county of Greene and State of Missouri, have invented a new and Improved Hose-Coupling for Cars, of which the following is a full, clear, and exact description.

This invention relates to couplings for connecting the cars of a train, the purpose of the invention being to provide efficient means for connecting the air-hose and other hose which should run through the train.

The object of the invention is to produce a coupling of simple construction which will couple automatically when the cars are brought together and which will have a desirable flexibility, adapting the device for the passing of curves and enabling it to accommodate itself to roughnesses in the road-bed.

The invention consists in the construction and combination of parts to be more fully described hereinafter and definitely set forth in the claims.

Reference is to be had to the accompanying drawings, forming a part of this specification, in which similar characters of reference indicate corresponding parts in all the views.

Figure 1 is a vertical central section taken through two adjacent cars at the coupling and showing our hose-coupling applied thereto. Fig. 2 is a bottom plan of the parts shown in Fig. 1. Fig. 3 is a horizontal section, upon an enlarged scale and passing through the principal parts of the coupling, representing the same in the act of coming together. Fig. 4 is a side elevation of one of the parts shown in Fig. 3, but with a spring, to be referred to hereinafter, represented as removed; and Fig. 5 is a section taken substantially on the line 5 5 of Fig. 3.

Referring more particularly to the parts, 1 and 2 represent the adjacent extremities of two cars, the same being provided with a coupling 3 of any common construction. From the under side of this coupling 3 we support horizontally-disposed draw-bars 4 and 5, the bodies of which are disposed longitudinally on the central axis of the cars and beneath the coupling 3, as will be readily understood. These bars 4 and 5 are not attached together, but are simply supported, respectively, from the adjacent parts of the

coupling 3, so that when the cars are coupled together their ends lie adjacent. To the adjacent extremities of these draw-bars 4 and 5 we attach hangers 6. As shown in Fig. 1, these hangers consist of bars bent to angular form, so that each presents a horizontal arm 7 and a vertical arm 8. The horizontal arms 7 are attached by pivot-bolts 9 to the under sides of the draw-bars 4 and 5, as indicated. These hangers extend in opposite directions, so that the arms 8 thereof are disposed relatively from each other.

In the vertical arms 8 of the hangers openings 10 and 11 are formed, the said openings being arranged in horizontal alinement with the corresponding openings of the opposite hanger. In the openings 10 we mount the stems 12 of our coupler 13, and the rear extremities of these stems 12 are formed with a return-bend 14, so that tails 15 are provided projecting inwardly, and these tails 15 pass through the openings 11, as shown. These openings 11 are elongated vertically, so as to form slots.

To the adjacent extremities of the stems 12 coupling-heads 16 and 17 are attached, the construction whereof is most clearly shown in Figs. 3 to 5. These heads consist of massive blocks. The head 16 is formed with an inclined forward face 18, so that it presents the appearance of a wedge. The forward extremity 19 is formed into a pair of oppositely-projecting horns 20, which form a substantially V-shaped recess or throat 21 therebetween, the central axis of the said throat 21 being disposed in a horizontal plane, as indicated most clearly in Fig. 4.

Near the rear face 22 of the coupling-head 16 the inclined face 18 thereof is formed with a tongue 23, the same being tapered to its forward edge 24, so that it presents inclined faces 25. The side face 26 of this tongue constitutes a continuation of the side face of the block 16, the same being parallel to the opposite side face, as will be readily understood. To the outer face 26 we attach a spring 26^a, which projects forwardly and in the direction of the opposite coupling-head 17. The purpose of this spring will appear more fully hereinafter. Through the block or coupling-head 16 we provide ports 27, 28, and 29. The ports 27 and 29, which are disposed adjacent to the inclined face 18, emerge upon the rear face 22 of the coupling-head, at

which point suitable nipples 30 are provided, facilitating the attachment of hose, as will be readily understood. These ports 27, 28, and 29 emerge upon the inclined face 18, so as to 5 form openings 31, which are in alignment vertically, as indicated in Fig. 4. At a suitable point in the under side of the block or head 16 we provide a drip-valve 32, which communicates with the port 28. This port, it may 10 be said, is the port which carries steam through the train for heating purposes. This port 28, as indicated most clearly in Fig. 3, passes diagonally through the body of the block or head and emerges at the rear face 22, 15 at which point it is provided with a suitable nipple 33, facilitating the attachment of hose, as will be readily understood.

The coupling-head 17 is substantially similar to the coupling-head 16, except that it is 20 of opposite or complementary form. Opposite the throat 21 of the block 16 a tongue 34 is provided, which is similar in all respects to the tongue 23, already described. Opposite the tongue 23 a throat 35 is formed, which is 25 similar to the throat 21, the same being formed between projecting horns 36, as shown most clearly in Fig. 1. Through the body of the coupling-head 17 ports 37 are formed, which emerge upon the inclined forward face 38 of the head at the point 39, and these ports are adapted to align, respectively, 30 at this point with the openings 31 from the ports 27, 28, and 29, referred to above. The port 37^a in this case is situated to correspond with the port 28, which is the steam-port, and 35 is provided, like the port 28, with a similar drip-valve 40. The ports 37 emerge upon the rear face 41 of the coupling-head 17, at which point suitable nipples 42 are provided 40 for the attachment of hose. To the outer face 43 of the tongue 34 a spring 44 is attached, which is similar in form to the spring 36^a, referred to above.

The manner in which the coupling-heads 45 16 and 17 come together is most clearly shown in Figs. 1 and 2. As indicated, the inclined faces 18 and 38 come together. The tongue 34 of the head 17 is received in the throat 21 of the opposite head, while the 50 tongue 23 is received in the throat 35 of the head 17. In this way a very secure interlocking of the coupling-heads is brought about. In order to assist in maintaining an intimate union between the two, the springs 55 44 and 26^a are provided, the same being bent inwardly toward their ends, as shown, so as to exert a pressure upon the opposite faces of the heads for this purpose.

Near the rear portions of the stems 12 we 60 provide collars 46, which have substantially spherically-formed outer faces 47. Pressing against these collars we provide helical springs 48, which surround the bodies of the stems, as indicated. The inner extremities 65 of these springs thrust against the heads 16

and 17 and tend to force the same toward each other. As stated, the rear extremities of these springs 48 press against the collars 46 and normally maintain these collars in the openings 10, which openings constitute seats 70 or sockets for the same, as will be readily understood. From this arrangement it should be understood that the shock of bringing the coupling-heads 16 and 17 together is much reduced, as the springs absorb this force. In 75 this connection it should be understood that the tails 15 of the stems operate as guides in connection with the stems 12, enabling the same to move rearwardly. At the same time the tails 15 have the additional function of 80 maintaining the heads 16 and 17 in a plumb position.

As indicated in Fig. 1, the hose connections 49 for the steam, air, and gas are attached to the nipples on the rear faces of the coupling-heads.

With the arrangement described evidently a very flexible connection may be made between the hose and the adjacent cars. By reason of the pivot-bolts 9 the hangers 6 and 7 may adapt their positions for passing curves. At the same time the springs 48 take up any longitudinal movement of the coupling-heads in a front or rear direction. In order to normally maintain the coupling-heads in a normal or mid position, we provide chains 50, which are attached to eyebolts 51, carried, preferably, at the bends 14 of the stems 12, the opposite extremities of these chains 50 being attached to springs 52, 90 which are carried by the draw-bars 4 and 5, as shown. From this arrangement when the hangers 6 and 7 are displaced laterally, as in passing a curve, the springs 52 will be extended and will return the hangers and stems 100 to their normal positions when the train passes on to a straight section of the track. Similar chains 53 are arranged adjacent to the coupling-heads, which attach to the same, respectively, by means of eyebolts 54, 11 the outer extremities of these chains being attached to springs 55, carried by the under sides of the adjacent extremities of the draw-bars 4 and 5. These springs 55, of course, when extended by displacement of the coupling-heads tend to return the same to their normal mid-position. The fact that the stems 15 are carried in slots is advantageous, inasmuch as it enables the coupling-heads to be displaced more or less in a vertical plane, 1 so that they will adapt themselves to inequalities in the road-bed or to sudden changes of grade.

Having thus described our invention, we claim as new and desire to secure by Letters Patent—

1. In a hose-coupler for cars, in combination, a pair of brackets having substantially horizontal arms pivotally attached to a support and having substantially vertical arms 1.

- depending downwardly therefrom, stems guided upon said vertical arms, springs pressing said stems toward each other, coupling-heads attached to said stems and adapted to interlock, said coupling-heads having alining ports passing therethrough.
2. In a hose-coupler, in combination, a pair of pivotally-supported hangers having substantially vertical arms with openings there-
10 in, collars having rounded faces seating in said openings, stems guided through said collars, coupling-heads carried by said stems and adapted to interlock, springs surrounding said stems and thrusting against said col-
15 lars, said coupling-heads having alining ports passing therethrough, and hose in connection with said ports.
3. A hose-coupler comprising, in combination, a pair of pivotally-supported hangers having vertical arms with openings therethrough, stems guided through said openings, coupling-heads carried by said stems and adapted to interlock, springs surrounding said stems and forcing said coupling-
20 heads toward each other, said arms having other openings formed therein, and tails formed on said stems and guided in said last openings, said heads having ports adapted to aline.
- 25 4. In a hose-coupler, in combination, a pair of pivotally-supported hangers having substantially vertical arms, said arms having opposite alining openings, collars seating at said openings, stems guided through said collars and carrying interlocking coupling-heads, springs thrusting against said heads and said collars, said arms further having slots, and tails formed on said stems and projecting through said slots, said coupling-heads hav-
30 ing alining ports passing therethrough.
- 35 5. A hose-coupler comprising, in combina-
40 tion, a pair of pivotally-supported hangers,
- stems guided therethrough and having interlocking coupling-heads, chains attached to one of the aforesaid members, and springs 45 attached to said chains and affording means for maintaining said hangers in a substantially central position.
6. A hose-coupler comprising, in combina-
50 tion, pivotally-supported hangers, stems 50 guided thereupon and carrying coupling-
heads, chains attached to said stems and to said coupling-heads, and springs attached to said chains and affording means for maintaining said stems in a substantially central 55 position.
7. A hose-coupler for cars comprising a pair of coupling-heads having inclined abutting faces, said faces having forwardly-tapering tongues projecting therefrom, said heads 60 having horns presenting throats therebetween adapted to receive said tongues, and ports passing through said heads and emerging in alinement upon said inclined faces.
8. A hose-coupler for cars comprising a pair 65 of oppositely-disposed coupling-heads having inclined abutting faces with tongues project-
70 ing laterally therefrom, said heads having horns forming throats therebetween, respec-
tively receiving said tongues, and leaf-springs 70 attached, respectively, to each of said heads and engaging the opposite head, said heads having ports passing therethrough and emerging in alinement on said inclined faces.
- In testimony whereof we have signed our 75 names to this specification in the presence of two subscribing witnesses.
